(57) **CLAIM**

The ornamental design for a camera viewfinder, as shown as and described.

DESCRIPTION

FIG. 1 is a bottom perspective view of a camera viewfinder, showing our new design;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view shown with environment. The broken lines in the drawings depict portions of the camera viewfinder that forms no part of the claimed design. The additional broken lines shown in FIG. 9 are for the purposes of disclosing environment that forms no part of the claimed design.

1 Claim, 6 Drawing Sheets
